TYPEWRITING MACHINE

Jacob N. Hoffman, Bridgeport, Conn., assignor
to Underwood Elliott Fisher Company, New
York, N. Y., a corporation of Delaware

Application June 30, 1942, Serial No. 449,045

10 Claims. (Cl. 197—2)

This invention relates to typewriting machines and to typewriting-accounting machines and more particularly to machines of the so-called Elliott-Fisher type. Machines of this type usually comprise a rectangular platen frame, a substantially flat platen mounted in a substantially horizontal position in said frame for vertical movement therein, a line-space frame mounted on the platen frame for forward and rearward movement over the platen, and a type carriage mounted on the line-space frame for movement in opposite directions transversely of the platen in letter-spacing direction and return. In certain of these machines, power mechanism under control of a suitable key or keys is provided for returning the carriage to position to start a line of typing. The line-space frame is operated by the return movement of the carriage as the carriage approaches the end of said movement to move said frame and the type carriage carried thereby forwardly the distance required to start a new line of typing.

In machines of the Elliott-Fisher type, a brake is usually provided for the line-space mechanism which brake performs two functions. The brake holds the line-space frame stationary during the typing of a line and, also, prevents overthrow of the line-space mechanism with resulting variations in the spacing of the lines. This line-space brake is active during the line-spacing action of the line-space mechanism, and the line-space frame is moved against the action of the brake. The braking action or force varies considerably under different conditions, and these variations result in variations in the line-spacing movement of the line-space frame.

The primary object of the present invention is to improve the construction and mode of operation of typewriting machines, typewriting-accounting machines and similar machines to avoid the disadvantages in prior constructions above pointed out.

Another object of the invention is to provide typewriting machines and similar machines in which the type mechanism and the means for carrying the paper are moved relatively, after the completion of a line of printing, to line space and a brake is provided for the line-space mechanism, with means for controlling the brake to cause a substantially uniform line-spacing action at all times and under all conditions.

With the above and other objects in view, the invention consists in a machine embodying the novel and improved features, constructions and combination of parts hereinafter described and particularly pointed out in the claims, the advantages of which will be readily understood and appreciated by those skilled in the art.

The several features of the invention will be clearly understood from the accompanying drawings illustrating the invention in its preferred

form and the following detailed description of the construction therein shown.

In the drawings:

Figure 1 is a view in front elevation, with certain parts in section, illustrating certain portions of a typewriting machine of the Elliott-Fisher type to which the invention is applied.

Figure 2 is a detail view in front elevation, partly broken away and partly in section, illustrating a portion of the mechanism for actuating the line-space frame from the type carriage during the latter part of the carriage-return movement and showing the parts in their normal positions.

Figure 3 is a detail view in side elevation, partly broken away, and illustrating certain parts of the line-space mechanism with said parts in their normal positions.

Figure 4 is a view in front elevation, partly in section, illustrating certain parts of the line-space mechanism and the mechanism for controlling the line-space brake during the latter part of the return movement of the carriage.

Figure 5 is a view in front elevation illustrating a portion of the mechanism shown in Figure 4 with certain of the parts in different positions.

Figure 6 is a view similar to Figure 5 illustrating certain of the parts in still different positions, and

Figure 7 is a detail view in side elevation illustrating the line-space brake mechanism.

The invention is illustrated in this application as applied to a machine of the type illustrated and described in the patent to Foothrap, No. 1,904,127, dated April 18, 1933, and many of the parts have substantially the same construction as the corresponding parts of the machine illustrated and described in said patent.

The machine is provided with a carriage-return mechanism having substantially the same construction and mode of operation as the corresponding mechanism illustrated and described in the patent to Sundstrand No. 2,283,401, dated May 19, 1942. The line-space mechanism of the machine, except for the line-space brake and the mechanism for controlling the brake, has substantially the same construction, arrangement, and mode of operation of parts as the corresponding mechanism illustrated and described in the patent to Wise No. 2,248,152, dated July 8, 1941.

The machine illustrated in the present application comprises a platen frame provided with side bars or rails 2 connected by transverse bars and a substantially flat platen 6 mounted for vertical movement in said frame. Upon the side rails of the platen frame is supported a line-space frame movable forwardly and rearwardly on said rails to line-space the type carriage with relation to the platen. The line-space frame comprises side brackets or bars 8 connected by front and rear

rails of which the rear rail only is shown in this application and is indicated at 10. The line-space frame is provided with wheels or rollers which engage, respectively, the upper edges of the rails 2 of the platen frame to enable the line-space frame to be moved readily over the platen frame. Of these, the rear rollers are indicated at 12. The mechanism for moving the line-space frame comprises a shaft 14 rotatably mounted in bearings formed on said frame to which shaft the rollers 12 are secured, the shaft extending substantially parallel with the front and rear rails on the frame. On the shaft are fixed gears 16 which mesh with the teeth of racks 18 attached to the side rails 2 of the platen frame. The shaft is given a predetermined angular movement in a counterclockwise direction, Figure 3, adjacent the end of the return movement of the carriage to impart a line-space movement to the line-space frame.

The type carriage, a portion of which is illustrated in Figure 1 and indicated at 20, is provided with wheels or rollers 22 which engage the upper edges of the front and rear rails of the line-space frame so that the carriage is movable transversely of the machine along said rails to impart forward and return movements to the carriage. The carriage is connected by a flexible band 23 to the usual spring drum 25 which tends constantly to draw the carriage in a right-hand direction across the machine.

The machine embodying the present invention is preferably provided with automatically operating mechanism controlled alternatively by suitable keys or by the movement of the type carriage for imparting return movements to the carriage.

The mechanism for turning the shaft 14 to actuate the line-space frame comprises a wheel 26 attached to one end of said shaft and having a series of relatively fine teeth on its periphery which are engaged at intervals by a pawl 28 pivoted at 30 on a pawl carrier 32 mounted to turn on the shaft. A pawl actuating bell crank 34 is also pivoted on said shaft and is provided with a pin or stud 36 on one arm thereof engaging in a slot 38 in the outer portion of the pawl. The pivotal movement of the pawl 28, with relation to the pawl carrier 32, is limited by means of a pin 40 projecting from the pawl carrier and engaging in a recess 42 in the lower portion of the pawl. The pawl carrier and the pawl actuator are acted upon, respectively, by coil springs 44 which tend to swing the carrier and actuator in a clockwise direction, Figure 3. The pawl carrier and pawl actuator are normally held substantially in the positions shown in Figure 3 with the pawl in engagement with a stop 46 on the line-space frame, and the pawl is thereby held out of engagement with the toothed wheel 26.

In actuating the toothed wheel, the pawl actuator 34 is swung in a counterclockwise direction, Figure 3. During this movement of the actuator, the pawl is first engaged with the toothed wheel and the pawl carrier and toothed wheel are then turned with the pawl actuator until the movement of the pawl is arrested. The movement of the pawl is arrested to limit the line-space movement by means of a stop pin 48 mounted on a bracket 50 attached to the line-space frame and arranged to engage the forward side of the pawl. The engagement of the pawl with the toothed wheel 26, after the movement of the pawl is arrested, locks the line-space frame in

position. The pawl actuator is swung in a counterclockwise direction, Figure 3, to actuate the shaft 14 to impart a forward movement to the line-space frame, just before the completion of each return movement of the carriage, from the movement of the carriage.

The mechanism for actuating the pawl 28 from the carriage will now be described. The other arm of the pawl actuator is connected by a link 52 with one end of a lever 54 secured to the rear end of a rock shaft 56 mounted in bearings in the line-space frame and extending toward the front of the machine. The other end of said lever is connected by a link 58 to an arm 60 secured to the rear end of a relatively short rock shaft 62 also mounted in bearings in the line-space frame. To the forward end of shaft 62 is fixed an arm 64, which is connected by means of a coil spring 66 with the lower arm of a lever 68 pivoted to turn freely on the forward end of the shaft 62. The upper arm of the lever 68 is provided with a forwardly turned flange 70 which is arranged to be engaged by a pin 72 carried at the left-hand end of an actuating pawl or dog 74 pivoted on a stud 76 secured to a plate 78 forming a slide mounted on the line-space frame and movable transversely of said frame. The dog 74 is acted upon by a coil spring 80 which tends to swing the left-hand end thereof downwardly to carry the pin 72 into operative position with relation to the contact flange 70 on the lever 68, the movement of the pawl under the action of the spring being limited by means of a pin 82 projecting from the plate 84 secured to the slide 78 in spaced relation thereto, as shown in Figure 2.

During the entire movement of the carriage, except the first part of the advance movement and the last part of the return movement thereof, the slide 78 is held substantially in the position shown in Figure 2. After the first part of the advance movement of the carriage, and during the entire return movement thereof, the dog 74 is maintained by the spring 80 substantially in the position shown in said figure. As the carriage executes the last part of its return movement, the slide 78 is moved to the left with the carriage; and through the engagement of the pin 72 on the dog 74 with the contact flange 70 on the lever 68, the lever is actuated to impart a line-spacing movement to the pawl carrier 32 through the connections described. During the first part of the advance movement of the carriage, slide 78 is moved back to the right to its normal position shown in Figure 2. The slide 78 is provided with substantially parallel guide slots 86 and 88 in which engage, respectively, a guide stud 90 and the shaft 62, and the plate is held in position on the guide stud and shaft by means of holding plates or washers 94 and 96. The movement of the slide 78 toward the left is stopped by the engagement of the left-hand end of a projection or beak 95 on the slide with a fixed stop 97 secured to the right-hand end of the rear rail 10.

The mechanism for moving the slide to the left, from the position shown in Figures 1 and 2, during the last part of the carriage-return movement, comprises a draft rod 98 and mechanism for actuating said rod, during the return movement of the carriage having substantially the same construction and mode of operation as the corresponding mechanism disclosed in said Sundstrand and Wise patents, referred to above. The draft rod is mounted in a channel formed by the front face of the rear rail 10 and the

rear face of the carriage escapement rack 100. The right-hand end of the draft rod is connected by means of an attaching plate 102 to the slide 78. The left-hand end portion of the draft rod is guided by any suitable guide means (not shown).

The left-hand portion of the draft rod is provided with teeth upon its upper face and upon the draft rod are mounted a series of arresters 104, 106 and 108 of different heights engaging said teeth and adjustably arranged on the rod at different distances from the left-hand end thereof. The arrester 104 having the greatest height and located nearest the left-hand end of the draft rod is arranged to be engaged by the abutment plate 110 secured to the carriage 20 to arrest the carriage at the end of a full return movement thereof. The arresters 106 and 108 are arranged to be engaged alternatively by a check stop 112 mounted on the carriage and protrudable to different positions to engage selectively the said arresters at different points in the return movement of the carriage. Thus the return movement of the carriage will be arrested with the carriage in different positions, respectively, by the engagement of the abutment 110 with the arrester 104 and by the engagement of the protrudable check stop 112 with the arresters 106 and 108.

As the carriage approaches the end of its return movement, the abutment 110 on the carriage engages the arrester 104 or the check stop 112 engages one of the arresters 106 and 108 and the draft rod is moved to the left with the carriage thereby carrying the slide 78 therewith, and the carriage is finally arrested by the engagement of the projection 95 on the slide with the stop 97 which arrests the movement of the slide and the draft rod. During this movement of the slide, the line-space mechanism is actuated through the connections described to impart a line-spacing movement to the line-space frame.

The machine illustrated in the present application is provided with an electrical driving motor and with driving connections including a shiftable clutch for returning the carriage by power. The machine is also provided with carriage-return keys and mechanisms controlled by the keys, respectively, for projecting or protruding the stop 112 and for causing the engagement of the carriage-return clutch. The mechanisms for driving the carriage to return position and the mechanisms for controlling the engagement and disengagement of the carriage-return clutch and for controlling the position of the protrudable stop 112, in the present machine, have substantially the same construction, arrangement, and mode of operation as the corresponding mechanisms, illustrated and described in the patent to Sundstrand and the patent to Wise, referred to above.

The machine is provided with the usual line-space brake mechanism to hold the line-space frame firmly in position during the writing of a line and to prevent overthrow of the line-space mechanism during the line-space operation. The line-space brake mechanism comprises the rollers 12 which serve as brake discs or drums and brake shoes 114 arranged to engage, respectively, said brake discs. Each of the brake shoes is pivotally supported at 116 on an arm 118 pivoted on a pin or stud 120 mounted in a cylindrical boss 122 projecting inwardly from an upright 124 on the line-space frame. To each arm 118 is fixed, in spaced relation to said arm, a downwardly ex-

tending arm 126 and said arm is acted upon by a coil spring 128 which tends constantly to swing the arm forwardly and thereby engage the corresponding brake shoe with the brake disc 12.

5 To the lower end of each of the arms 126 is pivoted, at 130, the rear end of a push rod 132. Each push rod extends from the corresponding arm 126 forwardly and the forward portion of the rod engages in a guide 134 attached to the underside of the rear rail 10. The forward end of each push rod engages the rear side of a cradle or trough-shaped bail 136 having brackets 138 adjacent its ends, by means of which, the bail is pivoted at 140 to brackets 142 fixed to the forward side of the rear rail 10.

10 With this construction, the brake shoes 114 are normally held in engagement with the brake discs 12 so that the line-space frame is held firmly in position with relation to a work sheet, clamped to the platen, during the typing of a line. Upon a downward pressure of the forward portion of the bail 136, the push rods 132 are moved rearwardly and the arms 126 are swung rearwardly against the action of the springs 128 to release the brake shoes 114 from the brake discs 12. When the bail is released, the arms 126 are swung back forward by the springs 128 to engage again the brake shoes 114 with the brake discs.

15 In the present machine, as the carriage approaches the end of a return movement, the line-space brake is automatically released so that the line-space frame is free to move under the action of the line-space mechanism. The action of the line-space mechanism, therefore, is not subject to the variations in braking conditions usually met with, and a much more uniform line-spacing operation is obtained. At the extreme end of the line-spacing movement of the line-space frame, the line-space brake is again engaged so that it effectively prevents overthrow of the line-space mechanism.

20 The mechanism for controlling the line-space brake, during the latter part of the return movement of the type carriage, comprises a lever 144 pivoted at 146 upon a stud projecting forwardly from the rear rail 10 and having a forwardly bent portion 148 which overlies a finger 150 on a bracket or plate 152 attached to the forward side of the bail 136. The lever 144 is connected with a second lever 154 by means of a pin 156 secured in, and projecting forwardly from the lever 154 and engaging in a slot in the adjacent end of the lever 144. The lever 154 is pivoted upon a stud 158 secured in, and projecting forwardly from the rear rail 10, and the springs 128, acting on the arms 126, through the intermediate connections described, tend to swing the lever 154 in a clockwise direction, Figures 4 to 6, inclusive. The lever 154 is provided with a rearwardly bent projection 160, and the movement of said lever in a clockwise direction is adjustably limited by means of a set screw 162 threaded into a portion 164 of the line-space frame and arranged to be engaged by said projection. Pivoted on the stud 158 at the rear of the lever 154 is a third lever 166 and said lever is acted upon by a coil spring 168 which tends to swing the same in a clockwise direction, Figures 4, 5, and 6, the movement of said lever, under the action of the spring, being limited by means of a pin 170 projecting from the rear rail 10. The lever 166 is connected with the lever 154 to actuate the latter lever under certain conditions by means of a latch 172 slidably mounted on the

lever 166, the right-hand end of which latch is normally located above the left-hand end of the lever 154 in position to engage the latter lever upon a counterclockwise movement of the lever 166, as shown in Figures 4 and 5. The latch 172 is provided with slots 174 and is slidably mounted upon the lever 166 by means of studs 176 secured in the lever 166 and engaged in said slots. The latch 172 is acted upon by a coil spring 178 connecting the same with a pin 180 mounted on the lever 154 which tends to move the latch to the right, Figures 4, 5, and 6, to connect operatively levers 166 and 154.

With this construction, and with the parts in normal positions, as shown in Figure 4, upon depression of the left-hand end of lever 166, the latch 172 engages the left-hand end of the lever 154, and the latter lever is swung in a counterclockwise direction with the lever 166. This movement of the lever 154 swings the lever 144 in a clockwise direction, Figures 4, 5, and 6, and the forward portion of the bail 136 is depressed to release the line-space brake. Upon the release of the lever 154 by the latch 172, the line-space brake is again engaged by the action of the springs 128. As the carriage approaches the end of a return movement, the parts are located substantially in the positions shown in Figure 4, and the left-hand end of the lever 166 is depressed to actuate the lever 154 through the latch to release the line-space brake. As the carriage reaches the extreme end of its return movement, the latch 172 is moved to the left to carry the right-hand end of the latch beyond the left-hand end of the lever 154, thereby releasing said lever, and the line-space brake is again engaged by the action of the springs 128.

The mechanism for actuating the lever 166 comprises a roller 184 mounted in a block 186 attached to the downwardly extending arm of a bent plate or bracket 188 fixed to the left-hand end of the draft rod 98 by means of a box nut 190, and having a slot in which engages a guide plate 191 attached to the frame to guide the end of the rod and hold the same from upward movement. The block 186 carries a pin 192 to which is attached one end of a coil spring 194, the other end of which is connected to a point on the line-space frame. This spring normally retains the draft rod 98 and the plate 188 in their right-hand positions and restores them to said positions after they are moved to the left by the return movement of the carriage. The roller 184 is arranged to engage the upper edge of the lever 166 which is shaped as shown clearly in Figure 4. During the normal operation of the machine, the parts assume substantially the position shown in Figure 4. As shown in this figure, the roller 184 then occupies a lower portion of the upper edge of the lever 166. As the carriage approaches the end of a return movement, by the engagement of one of the abutments or stops on the carriage with one of the arresters carried by the draft rod, the draft rod is moved to the left, Figures 4, 5, and 6. The upper edge of the lever 166 is provided with portions 198 inclined, when the lever is in normal position, so that the leftward movement of the bracket 188 and the roller 184 depresses the left-hand end of the lever 166, thereby swinging the left-hand end of the lever 154 downwardly to release the line-space brake. The upper edge of the lever 166 is provided with a portion 200 which is engaged by the roll 184 after depression of the left-hand end of the lever. This portion 200 of the lever

constitutes a dwell portion, when that part of the lever to the left of its axis (Figs. 4, 5, and 6) is depressed, to hold the brake disengaged until the carriage reaches the extreme end of its return movement.

In order to disconnect the levers 166 and 154, when the carriage reaches the extreme end of its return movement, the slide 172 is formed with an upwardly extending projection 202 which is then engaged by the roll and the slide is thereby moved to the left to disengage the right-hand end of the slide from above the left-hand end of the lever 154. This releases lever 154 and the lever 144, and the line-space brake is then again engaged by the action of the springs 128.

As the carriage is moved forwardly following a return movement, the draft rod 98 is moved forwardly substantially to the position shown in Figure 4 by the action of the coil spring 194. During this movement of the draft rod, the movement of the roller 184, along the upper edge of the lever 166, allows the lever to be restored substantially to the position shown in Figure 4, by the action of the coil spring 194, and the latch 172 is then moved to the right into position above the left-hand end of the lever 154 by the coil spring 178. This restores the parts to their original, or starting positions.

It is to be understood that the invention is not limited to the particular construction and arrangement of parts of the illustrated form or embodiment of the invention, but that the invention may be embodied in other forms within the scope of the claims.

Having explained the nature and object of the invention, and having specifically described a construction embodying the invention in its preferred form, what is claimed is:

1. A typewriting machine comprising a supporting frame, a substantially flat platen, a line-space frame mounted on said supporting frame for movement forwardly and rearwardly over the platen, a type carriage mounted on the line-space frame for movement in letter-spacing direction and return, mechanism for advancing the carriage to letter space the same, means operated by the movement of the carriage for moving the line-space frame to line space adjacent the end of the carriage-return movement, a normally active brake for the line-space mechanism, and means for releasing said brake as the carriage approaches the end of its return movement and for restoring the brake at the extreme end portion of the line-space movement of the line-space mechanism.

2. A typewriting machine comprising a substantially flat platen, a line-space frame mounted for movement forwardly and rearwardly over the platen, a type carriage mounted on the line-space frame for movement in a right-hand direction to letter space and in a left-hand direction to return the same, mechanism for advancing the carriage to letter space the same, means operated by the movement of the carriage for moving the line-space frame to line space as the carriage approaches the end of the carriage return movement, a normally active brake for the line-space mechanism, and means for releasing said brake as the carriage approaches the end of its return movement and for restoring the brake immediately prior to the end of the line-space movement of the line-space mechanism.

3. A typewriting machine comprising a supporting structure, a substantially flat platen, a line-space frame mounted on said structure for

movement forwardly and rearwardly over the platen, a type carriage mounted on the line-space frame for movement in letter-spacing direction and return, means for advancing the carriage to letter space the same, mechanism for moving the line-space frame to line space, a normally active brake for the line-space mechanism, and means for releasing the brake during the greater part of the line-spacing action of the line-space mechanism and for restoring said brake just before the end of the line-space movement of said mechanism.

4. A typewriting machine comprising a frame, a substantially flat platen, a line-space carriage mounted on said frame for movement forwardly and rearwardly over the platen, a type carriage mounted on the line-space carriage for movement in letter-spacing direction and return, mechanism for advancing the type carriage to letter space the same, means for moving the line-space carriage to line space, a holding device for the line-space carriage, means for maintaining said device in action during the advance of the type carriage, and mechanism controlled by the movement of the type carriage for throwing said holding device out of action and for causing the restoration of said device to action.

5. A typewriting machine comprising a substantially flat platen, a line-space frame mounted for movement forwardly and rearwardly over the platen, a type carriage mounted on the line-space frame for movement in letter-spacing direction and return, mechanism for advancing the carriage to letter space the same, means for moving the line-space frame to line space, a brake for the line-space mechanism, means for normally maintaining the brake engaged, and mechanism for releasing the brake during the greater part of the movement of the line-space mechanism and for causing the restoration of the brake just before the completion of said movement.

6. A typewriting machine comprising a supporting structure, a substantially flat platen, a line-space frame mounted on said supporting structure for movement forwardly and rearwardly over the platen, a type carriage mounted on the line-space frame for movement in letter-spacing direction and return, means for advancing the carriage to letter space the same, mechanism for moving the line-space frame to line space, a holding device for the line-space frame, means for maintaining said holding device in action during the advance of the type carriage and during the greater part of the return movement thereof, said mechanism including a transverse draft rod mounted on the line-space frame and moved longitudinally during the return of the carriage, and means carried by the draft rod for rendering inactive said holding device during the greater part of the line-spacing action of the said mechanism.

7. A typewriting machine comprising a frame, a substantially flat platen, a line-space frame mounted for movement forwardly and rearwardly over the platen, a type carriage mounted on the line-space frame for movement in letter-spacing direction and return, means for advancing the carriage to letter space the same, mechanism for moving the line-space frame to line space, a normally active brake for the line-space mechanism, said mechanism including a transverse draft rod mounted on the line-space frame and moved longitudinally during the return of the

carriage, means for releasing the line-space brake, and mechanism carried by the draft rod for actuating said releasing means to release the brake during the greater part of the line-spacing action of the line-space mechanism and for causing restoration of the brake just before the line-spacing action of said mechanism is completed.

8. A typewriting machine comprising a supporting frame, a substantially flat platen, a line-space frame mounted on said supporting frame for movement forwardly and rearwardly over the platen, a type carriage mounted on the line-space frame for movement in letter-spacing direction and return, means for advancing the carriage to letter space the same, mechanism for moving the line-space frame to line space, a normally active brake for the line-space mechanism, said mechanism comprising a transverse draft rod mounted on the line-space frame and moved longitudinally during the latter part of the return movement of the carriage, a bail for controlling said brake, one or more levers for actuating the bail, and means carried by the draft rod for actuating and controlling said levers to release the brake during the greater part of the line-space action of the line-space mechanism and for causing the restoration of the brake immediately prior to the end of the line-spacing movement of said mechanism.

9. A typewriting machine comprising a substantially flat platen, a line-space frame mounted for movement forwardly and rearwardly over the platen, a type carriage mounted on the line-space frame for movement in letter-spacing direction and return, means for advancing the carriage to letter space the same, mechanism for moving the line-space frame to line space, a normally active brake for the line-space mechanism, means for controlling the brake during the latter part of the line-spacing action of the line-space mechanism comprising two cooperating levers, a latch movably mounted on one of the said levers for engaging the other lever to actuate the same, a spring for maintaining said latch in position to engage the latter lever, means for moving the first lever while the latch is in operating position to actuate the other lever to release the brake substantially at the beginning of the line-spacing movement of said mechanism and for actuating the latch to disconnect the levers to allow the restoration of the brake at the extreme end portion of the line-spacing movement of said mechanism.

10. A typewriting machine comprising a supporting frame, a substantially flat platen, a line-space frame mounted on said supporting frame for movement forwardly and rearwardly over the platen, a type carriage mounted on the line-space frame for movement in letter-spacing direction and return, mechanism for advancing the carriage to letter space the same, means operated by the movement of the carriage for moving the line-space frame to line-space adjacent the end of the carriage return movement, a normally active holding device for the line-space mechanism and means for rendering inactive said holding device as the carriage approaches the end of its return movement and for restoring said holding device to action at the extreme end portion of the line-spacing movement of the line-space mechanism.
